APPARATUS FOR ANCHORING, MOORING, TOWING OR OTHERWISE SECURING OR ATTACHING A LINE TO A BOAT

Thomas P. Brittain, 6606 44th Ave., University Park, Hyattsville, Md., and Robert N. Roley, 414 Rocky Place, Alexandria, Va.

Filed Jan. 3, 1962, Ser. No. 164,069

2 Claims. (Cl. 114—230)

This invention relates to boats and more particularly to apparatus for anchoring, mooring, towing, or otherwise securing or attaching a boat to a line.

In heretofore known types of apparatus employed to anchor, moor, tow, or otherwise secure or attach a small craft type of boat to a line, the line usually and normally passes from a cleat or bitt of the boat hull athwartships to the gunwale, through a fixed chock, and then overboard into the water so that a force is created which acts upon the boat to increase or amplify the pitching, rolling or yawing of the boat since the force created by such line is not acting through the center of gravity of the boat.

Accordingly, it is an object of this invention to provide apparatus which enables a line that is employed for anchoring, mooring, towing or otherwise securing a boat to be attached to the hull of the boat in a manner which enables the force created by the line to act through substantially the center of gravity of the boat so that pitching, rolling and yawing of the boat while anchored, moored, towed, or otherwise secured, is kept to a minimum.

An additional object of this invention is to provide a boat with apparatus which enables a line to be attached thereto at a location thereon which is along the fore and aft center line thereof adjacent the water line and fore of the bow of the boat.

A further object of this invention is to provide a boat with apparatus which enables a line to be attached thereto so that the boat will have a trim, when anchored, moored, towed, or otherwise secured, which is substantially the same trim that the boat has when underway.

It is also an object of this invention to provide a boat hull with apparatus that enables a line being employed to anchor, moor, tow, or otherwise secure the boat, as desired, to be effectively attached to the boat hull at a location thereon which causes the force created thereby to act substantially along the center line thereof so that the boat will have a minimum amount of roll, pitch and yaw, and enable the boat to have an effective trim, when so secured, such as the trim which the boat usually or normally possesses when the boat is underway being driven by its own power.

Another object of this invention is to provide apparatus for decreasing to a minimum any chafing effect on a line being employed to anchor, moor, tow, or otherwise secure a boat, as desired, by eliminating frictional sliding contact between the line and the hull of the boat.

Yet still another object of this invention is to provide apparatus which creates only rolling contact between a boat hull and a line being employed to anchor, moor, tow or otherwise secure a boat, as desired.

In order to accomplish the above stated objects and to overcome the disadvantages of existing known similar types of mechanism, the apparatus of this invention comprises an elongate bodily rigid rod-like structure which is removably secured to the boat hull with the structure being disposed in a generally vertical upwardly extending relationship, i.e. more vertical than horizontal, and fore of the bow of the boat with the lower end portion of the structure being disposed adjacent the load water line of the boat hull and the upper end portion of the structure extending above the deck of the boat hull ad-

jacent to and forward of the fore peak thereof. An anti-friction device is carried by each end portion of the structure with the anti-friction device that is adjacent the lower end portion thereof being secured thereto by means

5 which enables substantially universal movement of the lower anti-friction device relative to the structure. Securing means is provided for removably securing the structure to the boat hull with the structure being disposed in a plane which is substantially common to the 10 fore and aft center line thereof, and a line which may be employed to anchor, moor, tow, or otherwise secure the boat, as desired, is passed about the lower anti-friction device between the lower anti-friction device and the structure, then about the upper anti-friction device to the 15 side thereof which is opposed to the structure and then to a securement on the boat hull. By reason of the location of the lower anti-friction device, i.e., along the fore and aft center line of the boat hull adjacent to the load water line thereof, the force which is created by the 20 anchoring, mooring, towing, or securing of the line to the boat hull will act substantially through the center of gravity of the boat and accordingly will minimize any pitching, rolling or yawing of the boat.

Other objects, advantages and important features of 25 the invention will be apparent from a study of the specification following taken with the drawing which together describe, disclose and illustrate a preferred embodiment of the invention and what is now considered and believed to be the best mode of practicing the principles thereof. Still other embodiments or modifications of the invention 30 may be suggested to those having the benefit of the teachings, herein, and such embodiments or modifications are intended to be reserved especially as they fall within the scope and breadth of the subjoined claims.

35 In the drawing:

FIGURE 1 is a partial side elevational view of a boat having the apparatus of the invention employed therewith;

FIGURE 2 is an enlarged side elevational sectional view similar to FIGURE 1, and

FIGURE 3 is a partial plan view taken along the line 3—3 of FIGURE 2, looking in the direction of the arrows.

Attention is now directed to FIGURE 1 of the drawing wherein there is illustrated a boat 10 which is preferably of small craft type and which has removably secured thereto, as will be explained in more detail hereinafter, apparatus 12 which enables a line 14 that may be employed to anchor, moor, tow, or otherwise secure the boat 10, as desired, to be attached to the 45 boat 10 in a manner which enables a force which may be created by the line 14, when so attached, to act substantially through the center of gravity of the boat 10 and effectively decrease to a minimum the pitching, rolling, or yawing of the boat 10 when the boat is anchored, moored, towed or otherwise secured, as desired.

50 As illustrated in FIGURE 1 of the drawing, the boat 10 comprises a hull 16 having a load water line LWL, a deck 18, a keel 20 and a stem 22 with the stem 22 extending generally upwardly and forwardly from the keel 55 20 and terminating adjacent the deck 18 at a fore peak 24.

The apparatus 12 comprises an elongate bodily rigid rod-like structure 26, a lower 28 and an upper 30 bracket-like member each being adjustably secured to the 60 respective opposite end portions of the structure 26 by means 32 which may take the form of threaded portions and set screws, or the like, so that the over-all effective length of the apparatus 12 may be varied according to the size of the boat hull 16 and the location of the load water line LWL thereon.

65 The structure 26 having the bracket-like members 28, 30 adjustably attached thereto is removably supported by

the boat hull 16 through a lower 34 rod-like element and an upper 36 plate-like element with the rod and plate-like elements 34 and 36 each being secured to the boat hull 16 by suitable securing means 38 which may be in the form of screws, bolts, nuts, fairing blocks, etc., or the like, with the lower rod-like element 34 being disposed at substantially the load water line LWL of the boat hull 16 and the upper plate-like element 36 being secured to the deck 18 of the boat hull 16.

The upper plate-like element 36 has a part 40 thereof which extends forward from the deck 18 of the boat hull 16 and projects beyond the fore peak 24 thereof, and terminates in bifurcated or yoke-like end portion 42, note FIGURE 3 of the drawing, having spaced apart projections 44, 44 which define a recess 46 therebetween with the projections 44, 44 having aligned openings 48, 48 therethrough, at least one of which may be internally threaded.

The upper bracket-like member 30 is provided with a portion 50 which projects therefrom with the portion 50 having an opening 52 therethrough which registers with the openings 48, 48 of the projections 44, 44 when the portion 50 of the bracket-like member 30 is disposed within the recess 46 of the upper plate-like element 36. Retaining means 54 in the form of an elongate pin, thumb screw, or the like, having an externally threaded portion for threadably engaging the internally threaded opening 48, is provided for passing through the aligned openings 48, 48, 52 to retain the upper bracket-like member 30 removably secured to the upper plate-like element 36.

Suitable means 56, in the form of a chain, cord, or the like, is secured between the retaining means 54 and the upper bracket-like member 30 to prevent the loss of the retaining means 54 during use of the apparatus 12.

The lower rod-like element 34 extends through the boat hull 16 and terminates in a generally upwardly and outwardly projecting part 58 and the lower bracket-like member 28 is provided with a socket portion 60 for receiving the part 58 so that the elongated rod-like structure 26 is disposed in a generally upstanding substantially vertical position, i.e., more vertical than horizontal, and closely adjacent to and fore of the bow of the boat 10 with the upper bracket-like member 30 being adjacent the fore peak 24 and the lower bracket-like member 28 being closely adjacent the load water line LWL.

Further, an anti-friction device 62, in the form of a roller-like element, is rotatably mounted to a generally upwardly and forwardly projecting portion 64 of the upper bracket-like member 30 by a shaft 66 for rotation about a generally horizontally extending axis with the anti-friction device 62 being disposed along the fore and aft center line LL of the boat 10.

Another anti-friction device 68, also in the form of a roller-like element, is carried by the lower bracket-like member 28 and is connected thereto by universal-type connection means 70 which may be in the form of interlocking eye bolts, or the like, with the anti-friction device 68 also being in a plane common to the fore and aft center line LL of the boat 10 and disposed closely adjacent to the load water line LWL.

It is of interest to note that the rod-like structure 26, the lower 28 and the upper 30 bracket-like members, the lower 34 rod-like and the upper 36 plate-like elements, and the anti-friction devices 62 and 68 are all disposed in a generally vertically disposed plane, i.e., more vertical than horizontal, which is substantially common to the fore and aft center line LL of the boat 10.

The line 14 which may be an anchor, mooring, towing, or some other suitable line for securing the boat 10, as desired, passes about the lower anti-friction device 68 to the side thereof which is common to the boat hull 16, and then generally upwardly and forwardly to the upper anti-friction device 62 and passes thereabout on the side opposite the boat hull 16 and then to some

part of the boat hull whereat the line 14 is secured by a securement 72, such as a samson post, bitt, or the like.

From the above, it is to be noted that a force which may be created through the attachment of the line 14 to the boat 10 will act in a direction that is substantially through the center of gravity of the boat 10 so that all pitching, rolling or yawing of the boat 10 will be decreased to a minimum amount.

Further, by reason of the fact that the line 14 passes about the anti-friction devices 62 and 68 in a manner which maintains the line 14 in a spaced relationship to all portions of the boat hull 16 until the line is secured thereto by the securement 72 all chafing due to sliding frictional contact of the line 14 and the boat hull 16 is reduced to a minimum since the contact between the line 14 and the boat hull 10 is only through the rolling frictional engagement of the line 14 with the respective anti-friction devices 62 and 68.

When not employed to anchor, moor, tow or otherwise secure or attach the boat 10 by the line 14, the apparatus 12 may be readily and easily removed from the boat hull 16 by merely releasing the attachment of the upper bracket-like member 30 from the upper plate-like element 36 by removing the retaining means 54 from the aligned openings 48, 48 and 52 and then lifting the apparatus 12 so that the part 58 of the lower rod-like element 34 is removed from within the socket portion 60 of the lower bracket-like member 28. In this way the apparatus 12 may be conveniently stowed or otherwise maintained for future use on the boat 10.

Also, the strain created by the force of the line 14, when attached or otherwise secured to the hull 16 to anchor, moor or tow the boat 10, will be distributed substantially throughout the forequarters of the vessel rather than directly on a bitt or cleat as in the usual or normal arrangements for anchoring, mooring or towing boats.

In addition, by so securing the line 14 to the hull 16 of the boat 10 as described, disclosed, shown and illustrated herein, less strain is imposed on a vessel which may be towing the boat 10.

While the invention has been described, disclosed and illustrated in terms of the preferred embodiment which it has assumed in practice, the scope of the invention should not be deemed to be limited by the precise embodiment herein shown, illustrated, described and disclosed and it is to be understood that other such embodiments are intended to be reserved especially as they fall within the scope of the claims herein subjoined.

We claim as our invention:

1. Apparatus for attaching a line to a boat hull at a location thereon which is substantially along the fore and aft center line thereof, said apparatus comprising an elongate, bodily rigid, rod-like structure, securing and adjusting means for removably and adjustably securing the rod-like structure in a generally upstanding position in a vertical plane substantially common with the fore and aft center line of the boat hull, said securing and adjusting means comprising lower rod-like and upper plate-like elements, upper and lower bracket-like members adjustably mounted on the end portions of the rod-like structure, said upper member having a recess for receiving a portion of the upper element, said lower member having a socket for receiving a part of the lower element, an anti-friction device carried by each end portion of the rod-like structure, and a universal connection between the lower of said anti-friction devices and the securing means, said adjustment means enabling the anti-friction devices to be positioned along the rod-like structure with the upper anti-friction device being disposed adjacent to and forward of the fore peak of such

boat hull and extending beyond the deck of the boat hull with the lower anti-friction device being disposed adjacent the water line thereof, whereby, a line may have an intermediate portion thereof pass about said anti-friction devices to enable one end portion of such line to be secured to the boat hull with the line being attached to the rod-like structure in a manner which enables a force created thereby to act substantially through the center of gravity of the boat hull.

2. Apparatus for attaching a line to a boat hull at a location thereon which is substantially along the fore and aft center line thereof, said apparatus comprising an elongate, bodily rigid, rod-like structure, securing and adjusting means for removably and adjustably securing the rod-like structure in a generally upstanding position in a vertical plane substantially common with the fore and aft center line of the boat hull, said securing and adjusting means comprising lower rod-like and upper plate-like elements, upper and lower bracket-like members mounted on the end portions of the structure, the upper element being disposed flat against and secured to the deck of the boat hull with the end of said upper element being of substantially yoke-like configuration and having aligned openings therein, the upper bracket having a portion thereof provided with an opening aligned with the openings of the yoke-like part of the upper element,

an anti-friction device carried by each end portion of the rod-like structure, and a universal connection between the lower of said anti-friction devices and the securing means, said adjustment means enabling the anti-friction devices to be positioned along the rod-like structure with the upper anti-friction device being disposed adjacent to and forward of the fore peak of such boat hull and extending beyond the deck of the boat hull with the lower anti-friction device being disposed adjacent the water line thereof, whereby, a line may have the intermediate portion thereof pass about said anti-friction devices to enable one end portion of such line to be secured to the boat hull with the line being attached to the rod-like structure in a manner which enables a force created thereby to act substantially through the center of gravity of the boat hull.
